(57) **CLAIM**

The ornamental design for a laptop computer, as shown and described.

DESCRIPTION

FIG. 1 is a top right front perspective view of a laptop computer, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is an enlarged view of the claimed portion thereof shown in FIG. 1; and,

FIG. 9 is an enlarged top left front perspective view of the claimed portion thereof.

The short dash-dot broken lines illustrating portions of the laptop computer form no part of the claimed design.

The dot-dash broken lines in the figures represent the boundary of the claimed design and form no part of the claimed design.
